UNITED STATES PATENT OFFICE.

CHARLES F. RITCHEL, OF BRIDGEPORT, CONNECTICUT, ASSIGNOR TO
INTERNATIONAL PERFECT ELECTRICAL SUPPLY COMPANY, A COR-
PORATION OF SOUTH DAKOTA.

TROLLEY-POLE.

SPECIFICATION forming part of Letters Patent No. 761,611, dated May 31, 1904.

Application filed September 17, 1903. Serial No. 173,637. (No model.)

To all whom it may concern:

Be it known that I, CHARLES F. RITCHEL, a citizen of the United States of America, and a resident of Bridgeport, county of Fairfield, 5 and State of Connecticut, have invented certain new and useful Improvements in Trolley-Poles, of which the following is a specification.

My invention relates to the trolley-carrying poles used on electric cars for making connection with overhead conducting-wires to conduct the electric current into the cars; and the object is to provide simple and efficient means for lateral vibration of the trolley-wheel relatively to the pole under the diverging movements of the pole relatively to the conducting-wire and at the same time support the axis of the trolley-wheel in such alinement with the trolley-pole that when in passing 10 under bridges and other low structures the pole has to be forced down to a level position, or thereabout, the contact of the trolley-wheel and conductor will not be interfered with, as where the trolley-wheel is carried on a laterally-swinging upper section of the pole that is cranked or deflected out of alinement with the axis of the pole to enable the trolley-wheel to be so swung by the deflections of the pole 15 relatively to the conducting-wire, as hereinabove described, reference being made to the accompanying drawings, in which—

Figure 1 is a side elevation of a trolley-car having the pole contrived in accordance with my invention. Fig. 2 is a detail in plan view 20 illustrative of the lateral action of the trolley-wheel. Figs. 3, 4, and 5 are details showing modifications of the connection of the vibrating part of the pole carrying the trolley-wheel with the main part of said pole.

40 A represents the main part of the trolley-pole. It is mounted in the usual manner on the top of the car, so as to swing vertically

on the pivot *b* to cause the wheel *c* to run in contact with the conducting-wire *d* under varying relations of the height of the wire and 45 the car. The pole is somewhat shorter than as ordinarily arranged and at its upper end carries a socket *e*, pendent therefrom in such acute angle to the pole that it is about vertical when the pole is in its normal relation to 50 the conductor. A forked extension *f* of the pole carrying the wheel *c* is mounted in this socket by a bent shank *g* of such angularity to the part *f* that said part *f* ranges in alinement with the rest of the pole, and yet the 55 trolley vibrates laterally better than when the socket is in alinement with the main part of the pole and the extension part is bent downward to provide the offset enabling the wheel to vibrate, and yet the wheel is carried sufficiently high for good contact with the wire even when the pole is forced down to the level 60 plane, which is not the case when the socket is in alinement with the main part of the pole and the extension part is offset, as the extremity of the main part is then higher than the wheel when the pole is forced down to any 65 material extent and prevents contact of the wheel and the wire.

In Fig. 4 I have represented the shank *g'* 70 of the extension part *f'* of the pole as capable of shifting vertically in the socket *e*, with a spring *h* to thrust it upward as an elastic structure to relieve the parts from shocks, and in Fig. 3 I show the extension part *f''* as consisting of a spring for the same purpose, the spring being held in the socket *e* by a pintle *i*, on which the spring may turn, or which may turn in the socket for the vibrations of 75 the trolley-wheel.

80 The extension part of the pole may have unlimited lateral vibrations in the socket, or the same may be limited, if desired, which may be provided for in any approved way, as

by a stud-pin *j* in the shank or pintle and a groove *k* in the socket, as shown in Fig. 5; also in Fig. 1.

What I claim as my invention is—

5 The combination in a trolley-pole, of a main part having the usual connection with the car, a laterally-vibrating extension of the upper end carrying the trolley-wheel and being normally in practical alinement with the main

part, and means for elastic support of said extension part on the main part of the pole.

Signed at New York this 2d day of September, 1903.

CHARLES F. RITCHEL.
